UNITED STATES PATENT OFFICE.

GEORGE C. HALE, OF KANSAS CITY, MISSOURI.

AUTOMATIC FIRE-ALARM SYSTEM.

SPECIFICATION forming part of Letters Patent No. 630,345, dated August 8, 1899.

Application filed December 3, 1898. Serial No. 698,175. (No model.)

To all whom it may concern:

Be it known that I, GEORGE C. HALE, a citizen of the United States, residing at Kansas City, in the county of Jackson and State of Missouri, have invented certain new and useful Improvements in Automatic Fire-Alarm Systems; and I do hereby declare the following to be a full, clear, and exact description of the invention, such as will enable others skilled in the art to which it appertains to make and use the same.

My present invention relates to improvements in automatic fire-alarm apparatus, the object of the invention being to provide means whereby the breaking out of a fire will act to cause the transmission of an audible signal, giving, in tones of the human voice, the exact location of the fire both to parties in the vicinity and, through the medium of a telephone system, to parties at distant points who may be in communication with the fire department.

In the drawings, Figure 1 is a diagrammatic view of a fire-alarm system embodying my present improvements. Figs. 2 and 3 are detail views of one arrangement or manner of mounting the phonograph or graphophone transmitter. Fig. 4 is a detail view of one form of thermostat which may be advantageously employed in my improved apparatus and system.

Before proceeding to a detailed description of the invention it may, generally considered, be briefly described as follows: In each of the rooms or apartments of a building in which my fire-alarm system is introduced is arranged a suitable number of thermostats, so arranged as to act only upon such a rise in the temperature as accompanies the breaking out of a fire. Any suitable form of thermostat may be employed. I prefer to employ one of the form illustrated in detail in Fig. 5, it consisting of two metallic bars or spring-like bands $a a'$. These are bowed or curved oppositely to each other and have their ends connected to a suitable insulating support a^2 . Each of the bars $a a'$ is provided on its inner surface with a lug or stud a^3 , and these serve as supports for a pivot-piece a^4 and an adjusting-screw a^5 . The bar a is connected with one side of an electric circuit

and the bar a' with the opposite side of said circuit, which is completed through the pivot-piece a^4 and pin or screw a^5 . When subjected to more than a predetermined degree of heat, 55 the bars $a a'$ will be separated a greater distance at their middle and the electrical connection through the parts $a^4 a^5$ will be broken. These thermostats are included in one or more local electric circuits, each of which includes also as many independent normally-energized magnets as there are apartments or rooms having their thermostats in that particular circuit. To the armatures of said magnets in these local circuits are connected 65 the transmitters or reproducers of a series of graphophone or phonograph cylinders, each of which bears a record giving the location of the particular portion of the building through which the thermostats on the particular circuit controlling the reproducer for that record are arranged. The breaking of any one of said local circuits by the action of a thermostat or other means included therein releases said armatures, and thereby 70 allows the transmitters or reproducers to fall into operative position on their respective cylinders. Said reproducers or transmitters are connected with a speaking tube or conduit leading to some selected portion of the 80 building (as to the office of a hotel, the watchman's room in a storehouse or business building, &c.) or have an outlet through an outer wall of the building, and said conduit is also connected with a telephone-transmitter which is included in the regular telephone 85 system, whereby the operator at the central or exchange office of such system will be instantly notified of the exact location of a fire.

Referring now to the drawings, in which 90 like letters and numerals of reference designate corresponding parts in the several figures, $A A' A^2$ designate three groups or sets of thermostats, I having for purposes of illustration shown my improved system as applied 95 to a building three stories high and as having a separate independent circuit and signaling apparatus for each floor. The thermostats A , which, for example, are arranged on the third floor of the building, are included in a local 100 circuit independent of the circuit including the thermostats A' on the second floor or those

indicated by A^2 on the first floor, although, as illustrated, a single battery B may be the source of current for all of said circuits.

In each of the above-described thermostatic circuits is included an electromagnet C , as will be plain by an examination of Fig. 1. These circuits are normally closed, and therefore the armatures C' connect the poles of their respective magnets C . A switch D is arranged in each of the local circuits referred to, whereby either of such circuits may be manually broken and the signal mechanism set in operation, in a manner to be herein-after described, when desired. The magnets C may be arranged at any desired point relative to the thermostats $A A' A^2$. Preferably all of said magnets are arranged in close proximity to each other in the room or inclosure wherein is situated the graphophone or phonographic signal device. This consists of a series of cylinders $E E' E^2$, all mounted on a common shaft F . The shaft F is provided with a gear-pinion f , with which meshes a gear f' , mounted on a driving-shaft F' . To this last shaft is connected a suitable motor F^2 . If desired, this motor may be a continuously-acting motor; but I prefer to drive the phonograph-cylinders intermittently or only when an alarm is to be sent in, and therefore have provided a stop or like device, that will be hereinafter described. Each cylinder bears a suitable record—for example, the location of the building to which the system is applied and in addition the particular portion of that building wherein are located the thermostats of that particular local circuit which controls the position of the transmitter or reproducer G adapted to transmit that record.

Various forms of connection between the armatures C' and the reproducers G may be provided. In the embodiment of the invention herein illustrated each of said armatures is carried by an arm or standard which is pivotally mounted on or connected with the back plate or base-piece c' of the magnet, and the armature C' of each magnet is connected, by means of a link C^2 , with one of the graphophone transmitters or reproducers G . These are pivotally supported, and the links C^2 are of such length that normally when the magnets C are energized and the armatures C' thereof against the poles the points g of the reproducers G will be held out of contact with the records on the cylinders $E E' E^2$, as shown in Fig. 3.

Any suitable pivoted mounting may be provided for the transmitters or reproducers G ; but at present I prefer to mount the same upon the tube or conduit H , by which the sound-signals produced from the graphophone-records are transmitted to the telephonic distributing system. As shown most clearly in Fig. 3 of the drawings, the tubular stem or body of each reproducer or transmitter G is provided with laterally-extending tubular trunnion-like portions G' , and these extend into the ends of adjacent sections of the

tube or duct H . The tube H is shown as extending from points adjacent to the cylinders $E E' E^2$ to a mouthpiece K , which opens through the outer wall of the building, so that any signal produced by either of said cylinders will be audible to a person passing or standing in the vicinity of said outlet K . With said tube or duct H is also connected an ordinary telephone-transmitter L , such connection being, in the embodiment of the invention herein illustrated, accomplished through a branch duct H' . This transmitter L is arranged in an electric circuit which includes also a magneto-electro generator M and is adapted, as will be hereinafter described, to be connected with the regular line or circuit connecting the telephone N with a central or exchange office.

To the shaft m of the generator M is geared a suitable motor O , and a brake or stop device P is provided for normally preventing rotation of said shaft. This stop device is shown as consisting of a bell-crank lever, one arm of which is adapted to engage with said shaft, while the other arm is connected with a lever-arm Q . To this arm is also connected one arm of a bell-crank lever P' , the other arm of which is adapted to act as a stop for holding the power-shaft F' of the graphophone signal apparatus stationary.

Various forms of motors may be employed for those herein indicated at $F^2 O$, I having for purposes of illustration presented a merely conventional showing of an ordinary spring or clock motor.

R designates an electromagnet which is arranged in a circuit including a battery S^2 and the wires $s s'$. The wire s of this circuit, which, as it is the means for assisting in the transmission of signals produced by the breaking of either of the hereinbefore-described local circuits, may be termed the "common" circuit, is connected with the armatures C' of the local-circuit magnets C , and the other wire s' is connected with a series of contact points or studs T , one being arranged adjacent to and in the path of each one of the said armatures C' . The armature S' of the magnet R is pivotally supported and is normally, by the action of springs $U U'$, held in engagement with the aforesaid lever-arm Q .

Whenever either of the local circuits is broken by the action of a thermostat or the manually-movable switch therein, the armature C' of the magnet C in that circuit, being released by gravity through the pull exerted by the reproducer G connected therewith, falls against its coacting contact-point T , and thereby connects the wires $s s'$ and energizes the magnet R . The latter draws the armature S' thereof out of engagement with and from the path of the lever-arm Q , which under the force or pull of the spring U is moved against two contact-points $V V'$, which are arranged at the terminals of wires $v v'$, that are connected with the wires $w w'$, leading from the telephone N . Such movement of the lever-arm Q also releases the shaft F' and

the magneto-generator M, and the action of the latter rings the call-bell of the telephone N, which call being transmitted over the wires w w' notifies the operator at the central office that connection for the purpose of transmitting speech should be made with the telephone N. As soon as such connection is made the record on the particular graphophone-cylinder whose reproducer has been brought 5 into operative position will be transmitted to the operator at the central station through the transmitter L and over the wires v v' w w'. When the magnet R is thus energized, the armature S' is drawn against the pole-pieces thereof and the lever Q, falling, releases the magneto-generator and the phonograph mechanism. The action of the magneto M causes a current to pass over the wire 1 to the wire 2 of the regular telephone-circuit and through the signal apparatus in the central office back over line-wire 3 and wire w' to contact V' and thence to the magneto-generator over or through lever Q and the wire connecting it with the said generator. 10 A portion of this current also passes through the subscriber's instrument N, ringing the signal thereon. The local current of the transmitter L is as follows: from the transmitter to the battery S, then through lever Q 15 to contact V, and from there through the primary circuit 5 of the inductive coil and over wire 6 back to the transmitter. This induces a current in the secondary circuit of the induction-coil, which travels over the wire 35 7 through a "condenser" or resistance at 10 and the wire w to one side of the main telephone-circuit. The secondary current returns over the opposite side of said main circuit to the wire w' and through the contact V' and lever Q back to contact V and wire v, that is connected with the secondary of the induction-coil. The operator in the central or exchange office is thus advised of the exact 40 location of the fire and can notify the fire department or connect the telephone N with the telephone at the fire-department headquarters, so that the signal will be transmitted directly from the burning building to the fire department. The signal will be repeated 45 50 until the motor F² has run down, and simultaneously with the transmission of the signal over the telephone system it will be delivered through the conduit or tube H and outlet K.

It is to be understood that the telephone N 55 is the regular office or business instrument employed for the transmission of all telephonic messages, and one of the important advantages incident to my system is that I am able to employ the regular telephone-exchange system to be found in all cities for transmitting fire-alarm signals.

Of course if desired to connect the above-described signaling mechanism with the fire-department headquarters, for example, direct 60 without going through the telephone exchange or central office, as I have pointed out, or where there is no established telephone

system, a separate circuit would be established for conducting the signal from the transmitter L.

By the term "graphophone" or "phonograph" herein I mean to include any of the various forms of apparatus now known for reproducing the human voice or other sounds which may be adapted for use in my improved 75 system.

I do not herein make any claim to the specific construction of the thermostat illustrated in the drawings as adapted for use with my improved signal apparatus.

Having thus fully described my invention, what I claim, and desire to secure by Letters Patent, is—

1. In an automatic fire-alarm apparatus, the combination of a telephone system, a thermostat, a phonograph having a cylinder bearing a record indicating the location of the thermostat, means controlled by the thermostat for normally holding the reproducer of the phonograph in inoperative position, and 85 a transmitter in the telephone system adapted to receive vibrations from the phonograph, substantially as set forth.

2. In an automatic fire-alarm apparatus, the combination of a telephone system or circuit, a series of electric circuits each including a suitable number of thermostats, a series of phonographs corresponding in number to the number of said circuits and each having on its cylinder a record indicating the location of the thermostats in the circuit with which that phonograph is associated, means, controlled by said circuits for normally holding the phonograph-reproducers in inactive 100 positions, a transmitter arranged in the telephone-circuit, and a conduit or tube connecting each of the phonograph-reproducers with said transmitter, substantially as set forth.

3. In an automatic fire-alarm apparatus and system, the combination of a telephone system, a thermostat, a normally closed electric circuit including the thermostat, a phonograph having on its cylinder a record indicating the location of the thermostat, means for normally holding said cylinder stationary, a 115 normally open electric circuit adapted to be closed when the thermostatic circuit is broken and when closed to release the locking means of the phonograph-cylinder, and a transmitter arranged in the telephone-circuit and 120 adapted to receive vibrations from the phonograph, substantially as set forth.

4. In an automatic fire-alarm apparatus and system, the combination of a telephone system or circuit, a series of local electric circuits, each including a suitable number of thermostats, a series of phonographs corresponding in number to said local circuits and each having on its cylinder a record containing information as to the location of the 125 thermostats in that circuit with which the particular phonograph is associated, means for normally locking said phonograph-cylinders against rotation, an electric circuit com-

- mon to all of said thermostatic circuits and connected with the locking means for the phonograph-cylinders, whereby when any one of the thermostats is actuated the locking means 5 will be withdrawn from the phonograph-cylinder associated with that thermostat, and a transmitter arranged in the telephone-circuit to receive the vibrations produced by the phonographs, substantially as set forth.
10. 5. In an automatic fire-alarm signal apparatus and system, the combination of a telephone-circuit, a thermostat, a phonograph having on its cylinder a record giving the location of the thermostat, an electric circuit including the thermostat, means controlled by said circuit for holding the reproducer of the phonograph in an inactive position, a telephone-transmitter arranged to receive vibrations from the phonograph, and another electric circuit including said transmitter and adapted, upon the action of the thermostat to connect said transmitter with the telephone system, substantially as set forth.
15. 6. In an automatic fire-alarm signal apparatus and system, the combination of a telephone system, a thermostat, a phonograph having on its cylinder a record giving the location of the thermostat, an electric circuit including the thermostat and devices for normally holding the reproducer of the phonograph in an inactive position, power devices for rotating the phonograph-cylinder, means for normally holding the cylinder stationary, a magneto-generator connected with a telephone in the telephone system, a motor for driving said generator, means for normally holding said generator stationary, a telephone-transmitter arranged to receive sound-vibrations from the phonograph, and another electric circuit including means for actuating the stop devices for the phonograph and magneto-generator motors, and adapted, on the action of the thermostat, to release said stop and connect the phonograph-transmitter with the telephone system, substantially as set forth.
20. 7. In an automatic fire-alarm signal apparatus and system, the combination of a thermostat, an electric circuit including the thermostat and an electromagnet, a phonograph having on its cylinder a record giving the location of the thermostat, connections between the armature of the electromagnet and the reproducer of the transmitter, whereby the latter is normally held in an inactive position, power devices for rotating the phonograph-cylinder, a telephone system, a telephone-transmitter arranged to receive sound-vibrations from the phonograph, and means controlled through the thermostatic circuit for setting in motion the phonograph power devices and for connecting said telephone-transmitter with the telephone system, substantially as set forth.
25. 8. In an automatic fire-alarm signal apparatus and system, the combination of a thermostat, a phonograph having on its cylinder a record giving the location of the thermostat, means controlled by the thermostat for normally holding the phonograph-cylinder stationary, and a speaking tube or conduit adapted to conduct sound from the phonograph, substantially as set forth.
30. 9. In an automatic fire-alarm signal apparatus and system, the combination of a thermostat, a phonograph having on its cylinder a record giving the location of the thermostat, power devices for rotating the phonograph-cylinder, means controlled by the thermostat for normally holding the phonograph-reproducer out of contact with the cylinder, and a speaking tube or conduit leading from the phonograph-reproducer, substantially as set forth.
35. 10. In an automatic fire-alarm signal apparatus and system, the combination of a thermostat, a phonograph having on its cylinder a record giving the location of the thermostat, means controlled by the thermostat for setting the phonograph in motion, and a tube or conduit leading from the phonograph to the exterior of the building or apartment in which the apparatus is placed, substantially as set forth.
40. 11. In an automatic fire-alarm signal apparatus the combination of a thermostat, a phonograph-cylinder bearing a record giving the location of the thermostat, an electric circuit including the thermostat and an electromagnet, a pivotally-mounted armature for said magnet, a pivotally-mounted reproducer for the phonograph-cylinder, a link connecting the said pivoted armature with the reproducer, means controlled by the thermostat-circuit for driving the phonograph-cylinder, and a speaking-tube leading from the phonograph-reproducer, substantially as set forth.
45. 12. In a fire-alarm apparatus, the combination of a series of thermostats, a series of phonographs each having on its cylinder a record giving the location of one of the thermostats, or groups of thermostats, a tube or conduit arranged adjacent to the phonograph for receiving messages or signals therefrom, the reproducer of the phonograph being provided with laterally-projecting, tubular, trunnions that engage with adjacent sections of said tube, connections between the thermostats and phonograph-reproducers whereby the latter are normally held out of contact with the respective cylinders, and means controlled by the thermostats for driving the phonograph-cylinders, substantially as set forth.
50. 13. In an automatic fire-alarm signal apparatus and system, the combination of a telephone system, a series of thermostats, a series of local normally closed electric circuits, each including one or more of said thermostats, and an electromagnet, a manual switch in each of said local circuits, a series of phonographs, corresponding in number to the local circuits, each having on its cylinder a record giving the location of the thermostat in the local circuit with which that phonograph is

associated, connections between the armature of the electromagnet in each local circuit and the reproducer of the phonograph associated with that circuit, whereby said reproducer is normally held out of contact with its cylinder, a speaking-tube for conducting the signals produced by either of the phonographs to another apartment or to the exterior of the building in which the apparatus is located, a telephone-transmitter, L, arranged to receive vibrations from said tube, a magneto-generator for sounding the signal-bell of a telephone in the telephone system, power devices for driving the phonograph-cylinders, stop

means for normally holding said power devices stationary and preventing action of the magneto-generator, a normally open electric circuit, adapted to be closed by the breaking of either of the local circuits, said circuit including said stop, and a branch circuit adapted to connect the transmitter, L, with the telephone system, substantially as set forth. 15 20

In testimony whereof I affix my signature in presence of two witnesses.
